UNITED STATES PATENT OFFICE.

JOHN L. CREVELING, OF WHITE PLAINS, NEW YORK, ASSIGNOR TO GOULD COUPLER COMPANY, A CORPORATION OF NEW YORK.

ELECTRIC REGULATION.

1,417,143.

Specification of Letters Patent. Patented May 23, 1922.

Application filed November 10, 1916, Serial No. 130,555. Renewed September 17, 1921. Serial No. 501,425.

To all whom it may concern:

Be it known that I, JOHN L. CREVELING, a citizen of the United States, residing in White Plains, county of Westchester, and 5 State of New York, have invented certain new and useful Improvements in Electric Regulations, of which the following is a description.

My invention pertains to that class of electric regulation wherein it is desired to regulate a dynamo or generator in a predetermined manner, and has for a particular object to provide means whereby the same will be automatically regulated within narrow 15 limits.

As my invention is particularly applicable to systems employing a generator to charge a storage battery and operate lamps or other translating devices in conjunction 20 therewith, and wherein the generator is subject to variations in speed, it will be described with reference to such a system.

In the drawing, Fig. 1 is a diagrammatic representation of one type of such system 25 chosen to illustrate one embodiment of my invention; and

Fig. 2 is a diagrammatic representation of a modification which may be made in the system of Fig. 1.

30 In the drawing, 1 represents a dynamo or generator the positive terminal of which is connected as by lead 2 with the positive side of the storage battery 3 and lamps or other translating devices 4. The battery 25 and translating devices have their negative terminals connected with the wire 5, carried to one terminal of the switch 6, the opposite terminal of which is connected as by lead 7 with one end of the coil or solenoid 8, the 40 opposite end of which is connected as by lead 9 with the negative side of the generator. The generator is provided with field energizing means, in this instance indicated as a shunt coil 10 having in series therewith 45 a suitable regulating resistance indicated as a carbon pile 11. It will therefore be obvious that the operation of the generator may be regulated by proper manipulation of the pressure and consequent resistance of the pile 11. 12 is a stud or pivot supporting 50 a T-headed lever having vertical arms 13 and 14 and the horizontal arm 15. The arm 13 bears against one end of the pile 11 and controls the pressure thereupon, the other 55 end of the said pile being confined by the

abutment or stop 16. The arm 14 carries at its free extremity a core of iron or other magnetic material 17, having one end pivotally united to said arm, and the other end supported by a rod of non-magnetic material 18, pivotally supported by the link 19. 60 20 is a coil or solenoid surrounding the core 17 and tending when energized to draw the said core in a right-handed direction so as to swing the lever 13—14—15 in a counter-clockwise direction about the pivot 12. 21 is a dashpot restraining too sudden movement of the said lever, and 22 is an adjustable spring tending to draw the lever 15 downwardly so as to revolve the same in 65 a clockwise direction to increase the pressure upon the pile 11. The free extremity of the lever 15, which is preferably made of non-magnetic material of light weight, as for example aluminum, is provided with an iron rod or keeper 23, pivotally connected therewith and normally drawn outwardly against the sheave or roller 24 as by the light leaf spring 25. 26 is an electromagnet which when energized attracts the keeper 23 and 70 firmly holds the same. The wire 27 is carried from the lead 2 to one end of the solenoid 20 and to the adjustable contact screw 28. The opposite end of the coil 20 is connected as by wire 29 with one end of the 75 winding of the coil 26 and with the adjustable contact screw 30. The remaining end of the coil 26 is connected as by wire 31 with one end of the resistance 32, the opposite 80 end of which is connected with the lead 9. 90 31 is also connected with the contact lever 33 normally resting upon the contact screw 28, in which position the said lever 33 and its connections through screw 28 serve to short-circuit the solenoid 20 and the electromagnet 26. And as I wind the said coils with fine wire, they will be practically de-energized when shunted out or short-circuited by the lever 33 but no large current will be consumed inasmuch as the resistance 32 100 is considerable and in series at all times with these circuits. Therefore when the lever 33 rests upon the screw 28, coil 20 will not exert any appreciable pull upon the core 17 and pile 11 will be tightly compressed 105 through the action of spring 22 drawing the lever 15 downwardly, and member 23 will rest against the antifriction roller or sheave 24, as shown in the drawing. If 33 be raised out of contact with 28, the short-circuit 110

around coils 20 and 26 will be broken and current will flow through the said coils. 20 will attract the core 17 and tend to swing the lever 14—13—15 in a counter-clockwise direction so as to relieve the pressure upon the pile 11, but will be prevented from doing so by coil 26 which will be energized simultaneously therewith and attract its keeper 23 and hold the same fixedly against its pole 10 pieces, which may be shod with non-magnetic material if desired. If contact lever 33 be brought into contact with the screw 30, coil 26 will then be short-circuited and the armature 23 immediately released, and 15 coil 20, further strengthened by withdrawal of the resistance of 26 from its circuit, will swing the lever 13—14—15 smoothly against the action of dashpot 21 and increase the resistance 11 until restrained, as for example 20 by breaking the circuit at 30—33, which will energize coil 26 and cause the keeper 23 to be attracted so as to hold the lever mechanism in a fixed position, or by bringing lever 33 into contact with 28, when both 20 25 and 26 will be short-circuited and spring 22 will exert the maximum pressure upon the pile 11. 41 is a fine winding or coil in shunt across a part of the system upon which it is desired to limit the voltage impressed by 30 the generator, and which in this instance is indicated as the generator main circuit. The coil 41 is provided with a core of iron or other magnetic material 34 and when energized tends to lift the same smoothly against 35 the action of the dashpot arrangement 39 cooperating with the end of the core. The core 34 is provided with a stem of non-magnetic material 35 which engages the contact lever 33 when core 34 is sufficiently raised. 40 And I so adjust the weight of the core 34 and the resistance 40 in series with the coil 41 that when the maximum desired voltage across the generator is reached coil 41 will lift its core 34 into contact with lever 33. 45 The coil 8 is provided with a core 36 similar to the core 34 and provided with a similar dashpot arrangement, and adapted when raised to operate the lever 33 in a similar manner. 37 is an adjustable resistance in 50 shunt across the coil 8 for the purpose of adjusting the operation of the same.

In Fig. 2 like numerals are used to indicate like parts, and the only modification intended to be brought out is the coil 38 shown 55 in series with the battery circuit, which may be used in place of the coil 8 of Fig. 1 in series with the generator circuit.

The switch 6 may be of any suitable type, and I prefer to use one of the usual automatic switches which will close its circuit when the voltage of the generator is substantially equal to that of the storage battery and open the circuit when the generator voltage falls very slightly below that of the 65 battery, in such manner as to prevent back

discharge from the battery through the generator. As these switches are well known in the art, and the particular type used forms no part of my present invention, details are purposely omitted for the sake of brevity. 70

An operation of my invention is substantially as follows:

If the generator be at rest or operating at sufficiently low speed, switch 6 will be open and the translating devices may be supplied 75 by the storage battery in a well known manner. If the generator have its voltage brought up until slightly in excess of that of the battery switch 6 will close and the generator will supply current to the battery 80 and translating devices, which current will return through the coil 8 and tend to lift the core 36. If the generator voltage be brought up until the generator delivers the maximum desired current, I so adjust the 85 resistance 37 that coil 8 will lift the core 36 smoothly against the action of its suitable dashpot into contact with the lever 33 and open the contact at 33—28, which will break the short-circuit around solenoid 20 and 90 magnet 26 and cause the same to be energized. Then if the current tends to rise, coil 8 will cause core 36 to further lift lever 33 and bring the same into contact with the screw 30 which will short-circuit the electro-magnet 26 and cause the same to release its armature 23, and coil 20 will instantly start to move the lever 15 smoothly against the action of dashpot 21 to increase the resistance of the pile 11 and cut down the generator 95 field until the current is at the normal and core 36 sinks sufficiently to allow the lever 33 to break connection with the contact screw 30, and thus, by breaking the short-circuit around 26, cause the same to instantly attract and hold its keeper 23 and prevent further movement of the lever 15 or change in the resistance 11, unless the current either rises sufficiently to cause 36 to bring 33 into contact with 30 again, or falls 100 sufficiently that 36 descends until 33 contacts with 28, which first action would further increase the resistance in the generator field and hold the current from exceeding its desired maximum, and which second action 105 would decrease the resistance in the field and tend to bring the generator current back to its normal strength. And, therefore, it will be noted that coil 8 and its cooperating parts will tend to cause the current supplied to the 110 system to remain constant. If at any time the voltage upon the system tends to increase above its desired limit for which proper adjustments have been made, coil 41 will raise the core 34, and by cooperating 115 with the lever 33 operate in a manner substantially identical with the current coil in controlling the generator to prevent the maximum desired voltage from being exceeded. And thus the current in the circuit, 120

- including coil 8, may be held from exceeding a predetermined limit, and the voltage across the circuit measured by the coil 41 can be automatically prevented from exceeding a predetermined limit within a very narrow margin, so long as the generator speed be sufficient, which is a very desirable type of regulation for use in systems of this character, chosen for illustration.
- 10 An operation of that modification shown in Fig. 2 is substantially the same as that outlined above, with the exception that it is the current in the battery circuit that is limited by the coil 38, instead of the generator current that is limited by the coil 8 in Fig. 1.

I do not wish in any way to limit myself to any of the exact constructions or details of operation given above to illustrate one embodiment of my invention, for it will be 20 obvious that wide departure may be made without departing from the spirit and scope thereof.

What I claim is:

1. Means for regulating a generator comprehending a regulating element, means for operating said element normally tending to increase the output of the generator, means for stopping and permitting the operation thereof, and electromagnetic means governing the operating means.

2. Means for regulating a generator comprehending a regulating element, means for operating said element normally tending to increase the output of the generator, means for stopping and permitting the operation thereof, and electromagnetic means governing the stopping and permitting means.

3. Means for regulating a generator comprehending a regulating element, means for operating said element normally tending to increase the output of the generator, means for stopping and permitting the operation thereof, and electromagnetic means governing the operating and stopping and permitting means.

4. Means for regulating a generator comprehending a regulating element, means for operating said element normally tending to increase the output of the generator, means for stopping and permitting the operation thereof, and electromagnetic means governing the operating means responsive to current fluctuations.

5. Means for regulating a generator comprehending a regulating element, means for operating said element normally tending to increase the output of the generator, means for stopping and permitting the operation thereof, and electromagnetic means governing the stopping and permitting means responsive to current fluctuations.

6. Means for regulating a generator comprehending a regulating element, means for operating said element, normally tending to increase the output of the generator, means

for stopping and permitting the operation thereof, and electromagnetic means governing the operating and stopping and permitting means responsive to current fluctuations.

7. Means for regulating a generator comprehending a regulating element, means for operating said element normally tending to increase the output of the generator, means for stopping and permitting the operation thereof, and electromagnetic means governing the operating means responsive to voltage fluctuations.

8. Means for regulating a generator comprehending a regulating element, means for operating said element normally tending to increase the output of the generator, means for stopping and permitting the operation thereof, and electromagnetic means governing the stopping and permitting means responsive to voltage fluctuations.

9. Means for regulating a generator comprehending a regulating element, means for operating said element normally tending to increase the output of the generator, means for stopping and permitting the operation thereof, and electromagnetic means governing the operating and stopping and permitting means responsive to voltage fluctuations.

10. Means for regulating a generator comprehending a regulating element, means for operating said element normally tending to increase the output of the generator, means for arresting the operation thereof, and electromagnetic means governing the operating means responsive to current and voltage fluctuations.

11. Means for regulating a generator comprehending a regulating element, means for operating said element normally tending to increase the output of the generator, means for arresting the operation thereof, and electromagnetic means governing the arresting means responsive to current and voltage fluctuations.

12. Means for regulating a generator comprehending a regulating element, means for operating said element normally tending to increase the output of the generator, means for arresting the operation thereof, and electromagnetic means governing the operating and arresting means responsive to current and voltage fluctuations.

13. The combination with a generator and a regulating element for affecting the same, of means for operating the said element to increase the activity of the generator, means for operating said element to decrease the activity of the generator, means for controlling the operation of both said operating means, a device controlling said controlling means, and electromagnetic means controlling said device independently responsive to voltage and current fluctuations.

14. The combination with a generator and storage battery charged thereby, of means for regulating the generator, electromagnetic operating and electromagnetic controlling means therefor, means for affecting the operation of said operating and controlling means, voltage responsive means for operating said affecting means, and current responsive means for independently operating the same.
15. The combination with a variable speed generator and storage battery charged thereby, of means for limiting the current and voltage of the generator comprising a regulating element, means normally tending to operate said element to decrease the resistance thereof, means for controlling said last-named means, electromagnetic means for operating the element to increase the resistance thereof, circuit changing means for controlling said electromagnetic means and said controlling means, voltage responsive means for operating said circuit changing means, and current responsive means for operating said circuit changing means.
16. The combination with a variable speed generator and storage battery charged thereby, of means for regulating the generator to limit the current and voltage thereof comprehending a carbon pile, electromagnetic means causing the pressure upon said pile to be varied and controlling means therefor operating upon changes in electrical connections thereof, and means for changing the said connections affected by voltage and current fluctuations.
17. Means for regulating a generator comprehending a regulating element, mechanical means normally tending to operate said element to increase the output of the generator, electromagnetic means arresting and permitting operation of said mechanical means, and electromagnetic means operating said element to decrease the output of the generator combined with means for affecting the electromagnetic operating means and the stopping and permitting means in response to voltage and current fluctuations whereby voltage and current in a circuit supplied by the generator may be held from exceeding predetermined limits.

JOHN L. CREVELING.
